INVENTOR

William L. Sharp,
By Archworth Martin,
Attorney.

UNITED STATES PATENT OFFICE

WILLIAM L. SHARP, OF STEUBENVILLE, OHIO, ASSIGNOR TO THE OHIO FOUNDRY & MANUFACTURING COMPANY, OF STEUBENVILLE, OHIO, A CORPORATION OF OHIO

STOVE

Application filed September 25, 1929. Serial No. 395,035.

My invention relates to stoves, and more particularly to those of the gas heater type.

Various types of gas heaters consist of a supporting metal framework, a clay backwall, and burner tubes or radiants disposed in front of the backwall and above a burner that is supported by the framework. In these types of heaters it is necessary to firmly anchor the backwall, which is of very great weight, to the framework to prevent displacement thereof.

My invention has for its object the provision of an improved means for fastening the backwall to the framework of the stove.

One manner in which my invention may be practised is shown in the accompanying drawing, wherein Figure 1 is a front elevational view of a heater; Fig. 2 is a view taken on the line II-II of Fig. 1, and Fig. 3 is a view taken on the line III-III of Fig. 2.

The framework 4 of the stove may be of any well-known form of construction. A backwall 5 is supported on the framework and is provided in each end with a horizontally-extending groove 6. Metallic anchor plates 7 serve to hold the backwall in place upon the framework 4 and to this end are provided with ribs or lugs 8, the ribs or lugs 8 fitting within the grooves 6.

The anchor plates 7 are of angular form in cross section and are also of decorative form. Each of the plates is provided with a front flange 9 which lies against the adjacent front face of the backwall 5, and with a rearwardly-extending portion 10 upon which a rib 8 is formed and which fits against the adjacent end surface of the backwall 5.

The portions 9 and 10 of the clamping plates 7 are each provided with a laterally-extending flange that rests upon the base or frame 4 and serves to brace the anchor plate and the backwall against tilting movement. Each of the plates 7 is fastened to the framework 4 by a bolt 11 that extends through the base portion of the clamping plate and through the frame 4.

The clamping plates 7 therefore securely hold the backwall 5 against shifting movement upon the framework 4 and against tilting, by reason of the angular formation of

such plates and by reason of the ribs 8 thereof that fit within the slots 6 of the backwall.

The front portion of the backwall 5 is recessed for the reception of ordinary tubes or radiants 12 in the usual manner which are disposed above a gas burner (not shown on the drawing).

It will be understood that the slots 6 and the ribs or lugs 8 may be made of any desired length and that various other changes may be made in the structure without departing from the spirit and scope of the invention as defined in the accompanying claims.

I claim as my invention:

1. Heater structure comprising a frame, a backwall supported on said frame and having horizontally offset portions, and clamping plates detachably secured to said frame and having horizontally offset portions in engagement with the first-named offset portions.

2. Heater structure comprising a frame, a backwall supported on said frame and having offset portions on its ends, adjacent to the front wall thereof, and clamping plates of angular form in horizontal cross section secured to said base, one flange of each of the said plates extending to the front of the backwall and the other flange extending against an end of the backwall and having an offset portion interlocking with the first-named portion.

3. Heater structure comprising a frame, a backwall supported on said frame and having offset portions in its ends adjacent to the front wall thereof, and clamping plates of angular form in horizontal cross section secured to said frame, one flange of each of the said plates extending to the front of the backwall and the other flange extending against an end of the backwall and having an offset portion interlocking with the first-named portion, and each clamping plate having a horizontally-extending base portion resting upon the framework.

4. In a heater, the combination with a backwall having a groove formed therein, of a clamping plate having a rib extending into said groove, and means for securing said clamping plate to the frame.

5. In a heater, the combination with a back-wall having a horizontally offset portion adjacent to one corner thereof, of a clamping plate having a horizontally offset portion interlocking with the first-named offset portion, and extending around said corner, and means for securing said clamping plate to the frame.
10. In a heater, the combination with a backwall having a horizontally offset portion adjacent to one corner thereof, of a clamping plate having a horizontally offset portion interlocking with the first-named offset portion and extending around said corner, and means for securing said clamping plate to the frame, the said clamping plate having a horizontally extending base portion in abutting engagement with the said frame.
15. In testimony whereof I, the said WILLIAM L. SHARP, have hereunto set my hand.

WILLIAM L. SHARP.
